UNITED STATES PATENT OFFICE.

CHARLES T. SCHOEN, OF MOYLAN, PENNSYLVANIA, ASSIGNOR, BY MESNE ASSIGNMENTS, TO CARNEGIE STEEL COMPANY, OF PITTSBURG, PENNSYLVANIA, A CORPORATION OF PENNSYLVANIA.

ART OF MAKING METAL WHEELS.

No. 903,010.

Specification of Letters Patent.

Patented Nov. 3, 1908.

Application filed September 13, 1907. Serial No. 392,757.

To all whom it may concern:

Be it known that I, CHARLES T. SCHOEN, a citizen of the United States, residing at Moylan, in the county of Delaware and State of Pennsylvania, have invented a certain new and useful Improvement in Art of Making Metal Wheels, of which the following is a full, clear, and exact description.

The object of this invention is to manufacture solid car-wheels direct from the molten metal.

Generally stated, and as illustrating my present practice, the molten steel from the open-hearth or other furnace is formed into an ingot, which is placed in a soaking pit, and while still hot is transferred to a powerful shearing machine adapted to compress and shear off a blank, which is then transferred to first-operation roughing dies and thence to second-operation roughing dies by which a rudimentary wheel is formed, and then the axle-hole is punched and then the wheel rolled into finished shape in a suitable rolling mill, after which, when necessary, the wheel is dished or coned. From the furnace to the dishing apparatus, the metal is kept hot, and if, by any accident, it should cool down, it may be reheated before losing any material portion of its workable heat.

Owing to the use of heavy cars, carrying enormously heavy loads, as is the present practice, the wheels constitute a heavy operating expense item, and it is imperative that some practical scheme shall be developed whereby durable wheels may be economically produced in order to reduce this expense item and permit the railroads to meet the demands placed upon them for heavy and large capacity cars designed to be run at relatively high speed. Wheels made from preformed blanks that have to be heated before being shaped by dies, presses, hammering, rolling, and other means, too frequently are defective by reason of imperfections in the blank which escape the maker's inspection and only develop in use. The rim, of course, is the most vulnerable point.

The present invention proceeds upon the rational theory that, if there is no practical let down in the plasticity and initial heat of the material from the time it is obtained in form to handle from the melting furnace up to the time it leaves the wheel rolling mill, the cause of flaws in the rim will be

annihilated, and hence a wheel may be economically produced which will meet the requirements of the railroads.

In the accompanying drawings, illustrating the invention, in the several figures of which like parts are similarly designated, Figure 1 is a cross-section showing an open-hearth furnace in conventional way. Fig. 2 is a perspective view of one form of ingot. Fig. 3 is an elevation, partly in vertical section, of a combined reducing and shearing machine. Fig. 4 is a perspective view of the product of the machine of Fig. 3. Fig. 5 is an elevation of a forging press with the dies in partial vertical section. Fig. 6 is a cross-section of the product of the first-operation dies. Fig. 7 is a cross-section of the product of the second-operation dies. Fig. 8 is an elevation of a hub-punching press with a rudimentary wheel in position between the clamps, and the wheel and the clamps shown in vertical section. Fig. 9 is a cross-section of the wheel as it comes from the machine of Fig. 8. Fig. 10 is an elevation and partial vertical section of the rolling mill. Fig. 11 is a cross-section of the wheel as it comes from the machine of Fig. 10. Fig. 12 is an elevation of the machine for dishing or coning the wheel of Fig. 11, the dies being shown in vertical section. Fig. 13 is a cross-section of the dished or coned wheel as it comes from the machine of Fig. 12.

I wish to state here now that while I have shown a series of preferred mechanisms or machines for carrying out the invention, I do not wish to be understood as limiting the invention to the use of such machines. It will be understood, of course, that a plant equipped with these or equivalent mechanisms or apparatus will be most economically operated by arranging the apparatus substantially in the order or sequence illustrated in the drawings.

The furnace, Fig. 1, may be of the ordinary open-hearth variety, having the hearth 1, in which the molten metal 2 is contained. Steel is preferably used in carrying out the invention. The steel is poured off into ingots which are passed to a soaking pit, and when the ingot has assumed shape of such stability as to permit handling, it is passed to a shearing machine of the character illustrated in Fig. 3, the details of which machine form the subject of an application for

2

patent by another, but the essential features of which are a bed 3, on which the ingot is placed, and a pair of reducing and shearing rams 4 and 5, having in their adjacent faces 5 means which will first engage the end of the ingot and reduce it to circular form and thereby condense the metal and particularly the circumferential portion of the metal, and subsequently shear off the mass to approximately 10 the weight of the desired wheel, substantially as indicated in Fig. 4. To effect this operation, the upper ram 4 may be supplied with means for imparting to it pressure very largely in excess of the pressure 15 that moves the ram 5, so that the first movement of the rams will suffice to reduce the ingot circumferentially, and then while the ingot is held in the portion 6, the superior pressure of the ram 4 will carry down the 20 ram 5 and the shear-blades 7 and 8 will then be brought into play to cut off the blank. Next, the blank of Fig. 4 is placed in the matrix 9 on the die-bed or table 10 of the die-press, Fig. 5, and then the table is shifted over beneath the plunger of the press 5, 25 and the male die 11 is brought down so as to shape one face of the blank and form a hole in the center thereof, as indicated in Fig. 6. Then this blank is placed in the 30 matrix 12 of the pair of second-operation dies and the die-bed shifted again, so as to bring these second-operation dies into line with the plunger, and the male die 13 of the pair of second-operation dies is then operated 35 in conjunction with the matrix 12 to form the rudimentary wheel shown in Fig. 7. This rudimentary wheel is then placed in the punching-press of Fig. 8, and clamped therein between a bed-clamp member 14 and 40 a removable clamp member 15, and while so held, the punch 16 is operated to punch out the hole in the rudimentary hub and thus transform the rudimentary wheel of Fig. 7 into the punched rudimentary wheel of Fig. 45 9. This punched rudimentary wheel of Fig. 9 is then taken to the rolling mill, which may be of any approved construction, such as that indicated in outline in Fig. 10, and comprising among other things, a back roll 50 17, which operates against the blank 18, said rolling mill also having roller dies, not shown, which operate on the web of the wheel and on the rim and flange and hub, so as to properly roll and shape the wheel. 55 The engine parts 19 for driving the rolling mill may be of any approved construction, geared or otherwise coupled with the rolling mill proper for imparting the necessary motion to its several dies or rollers and other 60 moving parts.

As the wheel leaves the rolling mill it is of substantially the shape shown in Fig. 11.

Inasmuch as most car-wheels are dished or coned, the wheel as it comes from the rolling mill is subjected to the action of a press, substantially such as shown in Fig. 12, wherein there is a female die 20 and a male die 21, the latter being connected with a plunger so that when lowered against the flat wheel of Fig. 11 supported upon the die 20, the wheel will be dished or coned, as shown in Fig. 12, and more particularly, detached in Fig. 13.

Now, it is to be noted that in the manufacture of wheels in accordance with this invention, the product is never allowed to get cold 75 from the time it leaves the furnace or melting apparatus until it is finished. In the event of the blank being treated by any mischance requiring to be reheated, it will be sufficient to expose the blank to furnace heat sufficient 80 to restore its surface heat, but from a manufacturing view point, this is more economical than the cost of heating the blank from a cold state, and the cost is not more than ten per cent. or fifteen per cent. of heating from 85 the cold state.

By my invention of producing wheels direct from the molten metal, there is a saving of the rolling expense where the blank is first made from rolled metal, and there is a saving 90 where the blank is first produced as a casting, and, moreover, as already pointed out, there is infinitely less chance of imperfections or defects developing in the wheel after it is put into use. Moreover, there is 95 practically no waste or scrap. The use of the shearing machine also is beneficial in that the original stock is reduced to any desired extent and then immediately expanded in the forming dies, and the result is that 100 there is little or no liability of the blank developing cracks on its edges.

What I claim is:—

The art of making metal wheels direct from molten metal from the original heat, 105 which consists in shaping the molten metal and while still hot and plastic reducing it circumferentially by pressure and while under such pressure shearing off a mass approximately equal in weight to the finished 110 wheel and then forming the wheel therefrom by pressure.

In testimony whereof I have hereunto set my hand this twelfth day of September A. D. 1907.

CHARLES T. SCHOEN.
